WINDOW ADJUSTER

William J. Paulussen, Nufley, N. J.

Application November 28, 1951, Serial No. 258,550

20 Claims. (Cl. 292—261)

This invention relates to a window adjuster for holding a window sash in any position to which it may be moved.

For a great many years window sashes have been mounted and carried in frames within which channel spaces have been provided to receive weights made of cast iron and from 10 to 12 inches long and an inch and a half (1½) in diameter, these weights being attached to cords which are passed over pulleys in the upper part of the window frame and attached to a window sash through the medium of a groove terminating in a recess in the sash to receive a knot at the end of the cord weight. With this construction when a sash cord breaks as they frequently do, in some window of a house or apartment, it is a hard job to put in a new sash cord. As a matter of fact, applicant has found that very few men know how to do this, especially in an expeditious and proper manner. To take out the lower sash a side strip which is usually nailed onto the window frame, must be removed and the sash withdrawn. Then a string with a small weight attached to one end must be passed over the pulley at the top of the sash slideway and this weighted end of the string attached to a new sash cord and the same pulled up over the pulley and this end knotted and placed in the sash recess while the other end is attached to the sash weight. To get this cord the right length, so that the sash may be moved throughout its range of movement requires some experience. To replace a cord for the top sash is much harder, as side guide strips must be taken out and usually these are installed in rather tight fits. To make these repair jobs therefore requires quite some time even for one that really knows how to do it.

It is therefore the principal object of my present invention to provide a new and simple device which may be easily and quickly installed on window sashes already in existence. A further object of my invention is to provide a construction which can be utilized in newly constructed houses at a great saving compared with the cost of the old window constructions as will be seen from the description which follows:

In the description, Figure 1 is a front view on a much reduced scale of a general style of window now in use with my improvement applied thereto;

Figure 2 is a view of the upper right hand corner of Figure 1 showing my improved device applied to the window sash, the device being shown in substantially its full size;

Figure 3 is a section on the line 3—3 of Figure 2;

Figure 4 is a view on the line 4—4 of Figure 3;

Figure 5 is a view similar to Figure 4 but with certain of the parts in a different operative position;

Figure 6 is a perspective view of a plunger device forming an important part of my invention;

Figure 7 is a view similar to Figure 4 but of a modified form of construction;

Figure 8 is a view similar to Figure 7 but showing its application to a window sash to be used in a new window construction;

Figure 9 is a view on the line 9—9 of Figure 8;

Figure 10 is a view similar to Figure 8 but with a further modified form of construction;

Figure 11 is a view on the line 11—11 of Figure 10;

Figure 12 is a fragmentary view showing part of the finished window;

2

Figure 13 is a sectional view of a window construction with a new form of sash control;

Figure 14 is a view on the line 14—14 of Figure 13;

Figure 15 is a view similar to Figure 13 but with the parts in different positions of operation;

Figure 16 is a view on the line 16—16 of Figure 15;

Figure 17 is a plan view of a key utilized with the construction shown in Figures 13 and 15.

Referring now to the details wherein like numbers refer to corresponding parts, 1 represents generally an old style of window frame having an upper window sash 2 and a lower window sash 3 each having glass pane 4 which is shown in one piece but which may be composed of a plurality of individual panes held in place by the usual putty means. For use with the window sashes 2 and 3 to take the place of the sash cords, weights, pulleys, etc., I utilize a small, simple casing 5 of suitable metal such as aluminum. The casing has an upturned portion 6 at one end and an upturned portion 7 at the other end with a turned up side 8 while there is no upturned edge on the side 9. The casing 5 has two holes therein to receive mounting screws 10 and 11. Positioned within the casing 5 is a movable member or plunger 12 having an inturned loop forming a cam surface 13. The lower end of the plunger 12 which passes through a slot in the end 7 of the casing is bent over at 14 for the purpose to be presently described. Positioned within the casing 5 is a roller 15 preferably of a disc type of a suitable material such as gum wood or maple although this disc roller may be made of a satisfactory plastic or other material the main thing being that it has long wearing properties. As shown in Figure 4 the roller 15 rests on a smooth part of the screw 11 so that the vertical axis through the center of the roller and the center of the screw are displaced as shown by the drawing whereby the roller will of its own inertia be against the side piece 16 of the window frame. Normally as shown in Figures 2 and 4, the weight of the plunger 12 holds the cam surface 13 thereof against the roller and in continuous contact with the window casing 16 and any effort to move the sash, whether it be the lower or upper one, will be prevented by the gripping of the roller between the cam surface 13 and the window frame member 16. To move either of the sashes all that is necessary to do is to push upward on the end 14 of the plunger 12 and to free the roller 15 so that the sash may be moved to an open position. When this position is reached the plunger 12 is released and the roller moved back to holding position of the sash at the desired point.

From the foregoing description it will be readily understood that the device may be quickly and easily installed on any of the old window constructions now in use on homes and then should a sash cord break it is not necessary to replace it with a cord but just install one of these small adjusters.

In Figure 7 the construction is very much the same as heretofore described except that a pivoted lever 17 is used between the cam surface 13 and the roller 15, the screw 11 being moved to the left so that the roller 15 runs on the end 7 of the casing.

In Figures 8—11 inclusive, the adjuster has the casing 5 set into a side of the window sash by making a recess therein. Also the lever 18 is substantially the same as 17 and is pivoted at 19 to a stud fastened to the casing 5. Also the plunger 12 has its arm 14 extending outwardly through the side piece of the window sash whereby it may be engaged by the hand of an operator, however, it functions just the same as in Figures 4—7. In Figure 10 the plunger 12 is replaced by a lever 20 pivoted at 21 to the casing 5 and has its end 22 extending through the sash the same as the end 14 of Figure 8. In this construction a resilient member 23 fastened as by rivet 24 to the side of the casing acts to hold the lever 20 in normal engagement with the roller 15 keeping it in contact with the side of the window frame. The operation of this form of the invention is the same as in the previous figures referred to.

In the form of construction shown in Figures 13—17 a lever 25 is fastened as by a screw 26 in the top of the recess 27 cut in the side of the window sash. The oppo-

3

site end of the lever passes outwardly through the sash and has a downwardly bent end 28 which is positioned over and free from the glass 29 carried by the sash. The lever 25 is formed with two cam surfaces 30 and 31 which meet at a point 32 approximately midway of the length of the lever. At this central point an adjusting screw 33 is utilized to give the required tension to a spring 34 which is utilized to normally hold the cam surface 31 of the lever 25 against the roller 15a which is located at the bottom of the recess 27. Pivotaly mounted by a screw 35 is a bar 36 having an inturned end 37 that is adapted to engage a roller 15b which is positioned on the cam surface 30 of the lever 25. The bar 36 has an opening 38 therein to receive a key 39 utilized for moving the bar 36 about the pivot 35 for the purpose to be presently described. Positioned over the bar 36 which fits in a recess 40 in the sash, is a plate 41 held in place by screws 42. Plate 41 has a slot 43 therein to allow movement of the key 39.

In the operation of this structure it will be seen that with the bar 36 in the position shown in Figure 15 the roller 15b is in gripping or locking position with the inner edge of the window casing. To move the sash to open position the key 39 is inserted in the slot 38 and the bar 36 moved upwardly to engage the roller 15b as shown in Figure 13, whence it can be lifted to release position. Then by preferably pulling outwardly on the end 28 of the lever 25, the sash may be moved to an open position. On releasing the lever 25 and withdrawing the force from the window sash the roller 15a will move up to the dotted position shown in Figure 15 thereby locking the sash in the position desired and on returning the bar 36 to the position shown in Figure 15, the roller 15b will move back to locking position thereby giving a double lock on the window sash. To release the sash so that it can be moved to closed position from this double lock, the bar 36 should be moved to the upper part of the recess 40 which will move the roller 15b to release position, then by an upward push on the lever 25 and then an outward pull on the downwardly extending end 28 of the lever 25 to move it into the position shown in Figure 15, the roller 15a will be released and drop down to the idle position at the bottom of the recess 27.

From the foregoing description it will be seen that I have provided a very simple and relatively inexpensive means for controlling the operation of window sashes and since there is relatively nothing to break or get out of order, the repair work required is reduced to a minimum, and if any repairs have to be made, anyone can do it in a very short period of time. I have found from tests, that the device described herein will last a long time and give excellent results in the adjustment of window sashes.

I claim:

1. A window adjuster comprising a casing having one edge open, means for fastening the casing to a vertical side of a window sash with the open edge a short distance away from the adjacent side window frame, said casing carrying a single piece plunger having an internal loop within the casing forming a single cam surface, the plunger having one end extending outside the casing when mounted on the lower portion of the side of a window sash so the plunger can be raised and a roller of suitable material within the casing positioned so the cam surface of the plunger will engage the roller and cause it to lock the sash to the side of the window frame.

2. A window adjuster as set forth in claim 1 further defined in that the window sash may be lowered from open position by pushing upwardly on the extending end of the plunger whereby the roller is released from its gripping position on the window frame and the sash lowered.

3. A window adjuster as set forth in claim 1 further defined in that the plunger has a rectangular cross section with the long dimension part of the rectangular shaped plunger engaging the outer surface of the roller which is disc shaped, the width of the disc being substantially the same as the width of the plunger.

4. A structure for application to a window sash for holding the sash in any desired open position, said structure comprising, a casing type of holder having an opening in one edge toward the window frame, means for attaching the casing to a window sash near a vertical side of the window frame, a single piece member mov-

4

ably carried within the casing and having a releasing end protruding from the casing while its interior end carries a single cam surface, a roller preferably of the disc type of suitable material positioned within the casing in alignment with said opening therein, the roller being in engagement with said cam surface whereby the weight of the said member will move the roller into locking engagement with the window frame when the window is moved to an open position.

5. A structure for application to a window sash for holding the sash in any desired open position, as set forth in claim 4 further defined in that said cam surface is formed by a folded over end of the member and the protruding end is bent so as to form a stop for the upward movement of the member when it is moved to a position for releasing the roller from locking position.

6. A structure for application to a window sash for holding the sash in any desired open position, as set forth in claim 4 further defined in that said casing attachment means includes, a screw stud at the bottom portion of the casing, that part of the stud within the casing having a smooth surface for positioning the roller so the axis through the roller will be displaced vertically from the axis of said screw stud whereby the weight of the roller will position it for locking engagement on releasing the sash after an opening operation thereon.

7. A window adjuster comprising a casing having means for attaching it to a window sash closely adjacent the vertical side of the window frame, said casing carrying a member having one end extending without the bottom of the casing for the purpose described while its other and inner end is looped to form a cam surface, a roller of suitable material carried within the casing but adapted to extend through an opening in the casing so as to engage the said side of the window frame, the roller being automatically moved by the member cam surface through said opening into locking position when the window is moved in the usual way to an opening position as defined herein.

0 8. A window adjuster as set forth in claim 7 further defined in that the window sash is released from its locked position by pushing upwardly on the extending end of the member thereby allowing the roller to freely move onto a part of the said cam surface that is more remote from the window frame than that part of the cam surface which engages the roller when in locking position.

9. A structure for application to a window sash for holding the sash in any desired open position as set forth in claim 19 further defined in that said structure includes a casing type of holder having an opening in one edge toward the window frame, means for attaching the casing to a window sash near a vertical side of the window frame, a member movably carried within the casing and having a releasing end protruding from the casing while its interior end carries a cam surface, a roller preferably of the disc type of suitable material positioned within the casing in alignment with said opening therein, a lever pivotally supported from the upper part of and within said casing and passing between said cam surface and said roller so its inertia acts with the cam surface on said member to move the roller into locking engagement with the window frame when the window is moved to open position.

65 10. A structure for application to a window sash for holding the sash in any desired open position as set forth in claim 12 further defined in that said structure includes a casing type of holder having an opening in one edge toward the window frame, means for attaching the casing to a window sash near a vertical side of the window frame, said single piece member movably mounted within the casing and having one end protruding from the casing for manual engagement therewith, the roller being of the disc type of suitable material positioned within the casing in alignment with said opening therein and means acting on said single piece member to cause it to operatively engage said disc for the purpose described.

70

75

76

11. A structure as set forth in claim 12 further defined in that said means acting on said single piece member is a resilient member fastened to the casing and engaging said member to cause it to move the disc to window locking position.

12. A window adjuster including a roller preferably of the disc type, the roller being held in concealed position on a vertical part of the window sash so the roller

can be moved into engagement with an adjacent part of the window frame and releasable means comprising a single piece member having a cam surface co-operative with the roller to move the roller into holding position between this same cam surface and against said frame after the window sash is moved to an open position and released.

13. A window adjuster as set forth in claim 12 further defined in that said single piece means includes a single piece movable member having a cam surface acting when said movable member is used to move the roller, said movable member having a protruding end for engagement by an operator so the position of the roller may be varied to change the position of the window sash.

14. A window adjuster as set forth in claim 12 further defined in that said single piece means includes a lever type single piece member pivoted at one end and having its opposite end bent so as to protrude from the window sash over the glass, said roller being positioned so as to be engaged by that part of the lever member adjacent its bent end.

15. A window adjuster as set forth in claim 19 further defined in that the single piece member is a lever member pivoted at one end within a recess in a side of the window sash while its opposite end extends transversely through said sash side and terminates in a bent end, while said roller is of the disc type and positioned within the recess adjacent that part of the lever which extends through the sash, and a second disc type roller is positioned in the upper part of the recess below the pivoted end of the lever which has cam surfaces extending in opposite directions from approximately its midpoint between the normal position of said rollers for engaging said rollers, the rollers being normally in contact with a part of the window frame, spring means acting on the lever at said midpoint to cause it to engage the rollers and push them against the window frame, the upper roller being normally in locking position while the lower roller is substantially free, means for moving said upper roller into release position whereby the sash may be easily opened by a push or pull in the opening direction by keeping the lower end of the lever free from the lower roller, the sash being locked in opened position by allowing the lower cam part of the lever to

engage the lower roller so it will move on the lever cam surface to locking position.

16. A window adjuster as set forth in claim 19 further defined in that release means for the roller is provided and when said release means is moved from release position to neutral position at least one roller will move to locking position for an upward push on the sash.

17. A window adjuster as set forth in claim 19 further defined in that release means for the roller is provided and when the said release means is in release position at least one roller will move automatically to locking position on its co-operative cam surface when a downward acting force acts on the sash.

18. A window adjuster as set forth in claim 19 further defined in that release means for the roller is provided and when the said release means is in release position at least one roller will move automatically to locking position on its co-operative cam surface when a downward acting force acts on the sash, said roller being released from locking position by an upward push on the sash which can then be easily lowered by an inward pull on the lower bent end of the lever member.

19. A window sash adjuster for holding a sash movably carried in a frame in any desired position comprising at least one roller carried by the sash for engagement with a part of the window frame and a single piece means for moving the roller into and holding it in locking position.

20. A window sash adjuster for holding a sash movably carried by the frame in a desired position as set forth in claim 19 further defined in that, a pair of rollers are operatively positioned by a member of the frame and a lever carried by the sash, the lever having a pair of spaced cam surfaces one for each roller and means independent of the lever for moving one roller in cooperative relation with said moving means to a neutral position as and for the purpose described.
